UNITED STATES PATENT OFFICE.

ANTON ZUBRYD, OF JERSEY CITY, NEW JERSEY, ASSIGNEE OF ONE-HALF TO
PORFYRIJ KISELYCIA, OF JERSEY CITY, NEW JERSEY.

LIFE-BUOY.

1,347,240.

Specification of Letters Patent. Patented July 29, 1920.

Application filed October 6, 1919, Serial No. 328,724. Renewed June 1, 1920. Serial No. 335,765.

To all whom it may concern:

Be it known that I, ANTON ZUBRYD, a citizen of Poland, residing at Jersey City, in the county of Hudson and State of New Jersey, have invented certain new and useful Improvements in Life-Buoys, of which the following is a specification.

The primary object of the present invention resides in the provision of a life buoy 10 designed to be carried in collapsed form upon the deck of a ship and to be easily and quickly unfolded to its set up operative position for launching in the water and being designed for carrying a number of 15 passengers.

A further object of the invention consists in the provision of a life buoy preferably of spherical formation with manually operable oars projecting through the side walls there- 20 of at points below the transverse axis.

With the above and other objects in view, this invention consists in the novel form, combination and arrangement of parts herein- 25 fully described and shown in the accom- panying drawings, wherein like reference characters indicate similar parts through- out the several views.

In the drawings,

Figure 1 is an elevational view of a life 30 buoy constructed in accordance with the present invention, the same being shown in operative position floating upon a body of water.

Fig. 2 is a horizontal sectional view there- 35 of showing the water tight connection between the external propelling oars and the operating handles therefor and the hinged passenger platform.

Fig. 3 is a vertical sectional view of the 40 buoy and

Fig. 4 is an enlarged detail sectional view showing the hinge connections between the vertical horizontal hoops and one of the curved brace bars.

Referring more in detail to the accom- 45 panying drawings, there is illustrated a life buoy shown in Fig. 1 as being floated upon a body of water, the same comprising a body portion 1 of spherical formation having a door controlled entrance 2 and windows 3 formed therein above the horizontal axis while the upper end of the buoy 1 is pro- 50 vided with a trap door 4 provided for the purpose of positioning the signal lamp 5 upon the suspending hook 6 while propel- 55

ling oars 7 project over the sides of the buoy 1 at points adjacent the water line and being operable interiorly thereof.

The body portion of the buoy 1 includes a skeleton framework formed of crossed vertical hoops 8 and 9, the hoop 8 being immovably mounted upon the lower end of the vertically extending post 10 while the upper end is supported on the shaft 11 projecting upwardly of the post 10 and outwardly of the hoop 8 and carrying upon the upper end thereof, the suspending hook 6 for the signal lamp 5. The hoop 9 is supported upon the post 10 and shaft 11 but is adapted to be moved thereon when the buoy is collapsed. 70

A horizontal hoop 12 is arranged inwardly of the hoops 8 and 9 and is journaled diametrically of the outer hoop 8 upon the pins 13 extending therethrough, and the hoop 8 and is adapted to be moved on said pins 75 when the framework is collapsed to have the diametrically opposite free sides thereof, positioned adjacent the lower end of the post 10 and shaft 11. In order to hold the circular hoops 8, 9, and 12 in position to 80 maintain the buoy 1 in the spherical formation illustrated in Fig. 1, there is provided a plurality of curved brace rods extending from the horizontal hoop 12 to points beneath the same, four of these brace rods 85 being shown and designated by the numeral 14, the same being pivoted upon the pins 13 connecting the hoops 8 and 12 and upon similar devices 15 carried by the horizontal hoop 12, the lower free ends of the curved 90 brace bars 14 being provided with apertures adapted to register with apertures provided adjacent the lower sides of the hoops 8 and 9 and when in registration adapted to receive the pins 16 carried by chains 17 upon 95 the brace rods 14. With this arrangement, the skeleton framework is held in a spherical form and in a substantially rigid one.

In order to accommodate a number of passengers within the buoy and as a support 100 for the passengers, there is provided a platform formed of light sections 18 hinged together as at 19 upon the meeting edges with a central opening 20 provided therein for the passage of the post 10 with the second 105 wall of the opening 20 supported on the collar 21 formed on the post directly beneath the platform sections 18. When the sections 18 are lowered to assume an alined horizontal position as indicated in Figs. 2 110

and 3, the same are so retained by links 22 having pivotal connections 23 with the post 10 and carrying hooks at the free ends thereof for engagement in eyes 24 formed upon the upper face of the platform sections 18, a link 22 being provided diametrically of the post 10 to hold the platform sections 18 in lowered position. As illustrated in Figs. 2 and 3, stirrups 25 are arranged in circular series upon the platform sections 18 so that a person may steady himself while riding within the buoy and be able to secure a handhold upon the post 10.

When the device is floating in the water and it is desired to propel the same, the oars generally designated 7 include paddle sections 26 having a flexible tubular connection 27 with the interior of the buoy and handles 28 suspended interiorly of the buoy upon chains 29 have key-shaped ends adapted for insertion through the tubular connections 25 into sockets 26' of the paddles 26 whereby manipulation of the paddles causes the forward propulsion of the buoy.

The signal lamp 5 is suspended upon the hook 6. The framework above described is adapted to be covered by any type of waterproof material such as a rubberized reticulated fabric 31 which will completely close the framework and render the interior thereof waterproof.

When the buoy is carried upon the deck of a vessel the same is generally in collapsed form which is accomplished by removing the pins 16 from the registering openings in the curved brace arms 14 and the vertical hoops 8 and 9 so that the arms 14 may be moved upon their pivot pins 13 and 1, to lie adjacent the hoop 12, thus permitting a vertical swinging of the hoop 12 upon the pins 13 and a horizontal swinging of the hoop 9 upon the post and shaft 10 and 11, respectively, while the releasing of the links 22 permit the platform sections 18 to be swung upon the hinges 19 to lie adjacent the post 10. The device is easily and quickly set up to its operative position and may be suspended in the water by a hoop or cable passing through the lamp suspending hook 6 and removed when the buoy reaches the water. The passengers enter the buoy through the door opening 2 and stand upon the platform 18 with the feet supported in the stirrups 25 while access to the hook 6 is obtained by ascending the ladder 30 and passing through the trap door 4, the propulsion of the buoy being accomplished by the operation of the oar paddles 26.

While there is herein shown and described what is believed to be the preferable embodiment of the invention, it is nevertheless to be understood that minor changes may be made in the novel form, combination and arrangement of parts without departing from the spirit and scope of the invention as claimed.

What is claimed as new is:—

1. A life buoy comprising a framework formed of a plurality of hoops, curved brace arms extending between the hoops to maintain the same in set up position, a vertical post within the hoops, a platform hinged at opposite sides of said post and a waterproof covering for said hoops. 70

2. A life buoy comprising a framework 75 formed of a plurality of hoops, curved brace arms extending between the hoops to maintain the same in set up position, a vertical post within the hoops, a platform hinged at opposite sides of said post, a waterproof 80 covering for said hoops, stirrups carried by said platform, and brace rods extending between the post and platform.

3. A life buoy comprising a framework 85 formed of a plurality of hoops, curved brace arms extending between the hoops to maintain the same in set up position, a vertical post within the hoops, a platform hinged at opposite sides of said post, a waterproof 90 covering for said hoops, an entrance door and windows formed in the waterproof covering and a lamp signal suspending hook carried by the upper end of said post.

4. A life buoy comprising a framework 95 formed of a plurality of hoops, curved brace arms extending between the hoops to maintain the same in set up position, a vertical post within the hoops, a platform hinged at opposite sides of said post, a waterproof 100 covering for said hoops, flexible tubes carried by said waterproof covering and oar blades fixed to said tubes.

5. A life buoy comprising a framework 105 formed of a plurality of hoops, curved brace arms extending between the hoops to maintain the same in set up position, a vertical post within the hoops, a platform hinged at opposite sides of said post, a waterproof 110 covering for said hoops, flexible tubes carried by said waterproof covering, oar blades fixed to said tubes, and handles for the oar blades carried within said framework and adapted to be extended into said tubes for engagement with the oar blades.

In testimony whereof I affix my signature. 115
ANTON ZUBRYD.
